UNITED STATES PATENT OFFICE.

RALPH S. THOMPSON AND CARL F. DOSCHER, OF NEW YORK, N. Y.

VACUUM CUP.

Application filed March 28, 1922. Serial No. 547,416.

To all whom it may concern:

Be it known that we, RALPH S. THOMPSON and CARL F. DOSCHER, citizens of the United States, residing at New York, in the county 5 of New York and State of New York, have invented certain new and useful Improvements in Vacuum Cups, of which the following is a specification.

This invention has reference to improvements in vacuum massage cups, which may, if so desired, be self applied to the body to produce a suction pressure and may be so manipulated as to produce a massage effect in conjunction with the vacuum pressure.

15 In accordance with the invention, there is provided a vacuum cup structure made in the main of relatively soft or resilient rubber having a manipulating head at the small end and at the large end a diaphragm serving as a closure therefor and of relatively unyieldable material. The diaphragm is of a diameter approximating that of the mouth of the cup and is provided in the plane of the outer face of the diaphragm, which coincides with the outer margins of the cup, with concentric series of alternate ridges and grooves with the ridges about flush with the outer face of the diaphragm and the grooves sunken below such surface so that 20 when the cup is applied to the flesh the ridges will bear against the flesh of the user and passages extending through the inner walls of the grooves communicate with the interior of the cup will, upon pressure applied to the small end of the cup, and the yielding of the latter produce vacuum conditions within the cup, which conditions, after production and on being maintained, establish such vacuum conditions in direct 25 contact with the flesh through the grooves and communicating passages leading thereto.

The body of the cup and all but the diaphragm being composed of relatively soft 30 rubber will readily yield to pressure tending to move the small end of the cup toward the diaphragm, and the small end of the cup being provided with an air passage capable of being closed by the hand of the operator will 35 maintain the vacuum conditions so long as

the operator desires. Such vacuum conditions may, however, be relieved at any time by the removal of the hand of the operator.

The invention will be best understood from a consideration of the following detailed description taken in connection with the accompanying drawing, forming part of this specification, with the understanding that the invention is not confined to any strict conformity to the showing of the drawing, but may be changed and modified so long as such changes and modifications mark no material departure from the salient features of the invention as expressed in the accompanying claims.

In the drawings:—

Figure 1 is a diametric section through the massage instrument.

Fig. 2 is a bottom plan view thereof.

Fig. 3 is a detail section illustrating in part the manner of manufacturing the cup.

Referring to the drawings, there is shown a vacuum cup 1 having a main body portion 2 which may be constructed of relatively soft or resilient rubber.

The vacuum cup is hollow, with a head or hand hold 3 at one end and a diaphragm or closure 4 extending across the other end, such diaphragm being formed of relatively hard or unyielding rubber or other material which will not be unpleasant or harmful to the flesh of the user.

The outer face of the diaphragm 4 is substantially in one plane substantially flush with the outer margins of the cup and provided with a series of ridges 6 and grooves 7 arranged concentric one with the other with each groove having a circular series of passages 8 therethrough.

One mode of manufacturing the cup is to produce the soft rubber body by one operation and the diaphragm 4 by another operation since the diaphragm is of a different nature from the body of the cup and may be made separately therefrom and afterward inserted and vulcanized in place so that the diaphragm 4 and the body 2 of the cup may be united in a substantially integral manner.

Through the central portion of the diaphragm 4 there is a relatively large open-

ing or passage 9 permitting the cup to be applied to portions of the body where accommodations are necessary for protuberances of more or less size.

5 Extending axially through the hand hold 3 by which the duct is manipulated, is a tapering air duct 10 having an enlargement 11 at the outer end, the enlargement 11 being of sufficient size to accommodate a finger 10 of the hand of the user.

The ridges 6 and grooves 7 are arranged concentrically in alternate order and through each groove 7 is a circularly arranged series of passages 8 through which 15 passages the interior of the cup and the outer face of the diaphragm 4 communicate by way of the passages 8.

In order to integrally unite the diaphragm 4 at its edges with the edges of the cup 2, 20 the diaphragm 4 is vulcanized to the inner surface of the cup at the margins thereof, as indicated at 12 so that no leakage may occur from the interior of the cup, especially when the passage 10 is held closed by the finger of 25 the operator.

When the vacuum cup or massage device is operated, the skeleton diaphragm 4 is pressed upon the person of the user with the opening 11 unclosed, and because of the 30 resiliency of the walls 2, the head 3 is moved into the cavity within the body 2 since this causes the forces of the air through the passages or duct 10 from the end 11 thereof, the finger of the operator being in the mean- 35 time moved out of the path of escaping air.

The forcing of the head 3 into the interior of the cup 2 and the pressing of the head 3 into the cup 2 produces vacuum conditions 40 within the cup 2 and these vacuum conditions are maintained by the placing of the finger of the operator upon the cavity 11.

The vacuum conditions thereby produced within the cup 2, especially when the end 11 of the duct 10 is closed by the finger of the 45 operator, produces a sub-atmospheric pressure within the cup 2, which pressure is exerted through the passages 8 upon the skin of the operator.

So long as the vacuum conditions are 50 maintained within the cup 2 by closing the upper end 11 thereof, the skin of the operator is subjected to a pulling action to be relieved whenever the finger of the operator is removed from the cup 11.

55 The effect of the vacuum conditions may be enhanced by a pulling or rocking of the cup 2 thus producing a massage effect, which effect may be broken at any time by removing the finger from the cavity 11.

60 The effect of the massage cup 2 has been found to be greatly improved by the combined suction and kneading effect produced, and such effect is found to be very beneficial for reducing superfluous flesh.

65 The combined vacuum effect and pulling

or agitation causes a rapid reduction of accumulations of flesh in various parts of the body to the benefit of the patient undergoing the vacuum cup treatment, whether such treatment be applied to the head, trunk, 70 or extremities of the body.

What is claimed is:—

1. A vacuum massage cup comprising a cup-shaped body of resilient material with an axial termination ending in a hand receiving head having an air duct leading axially therethrough, said cup having an expanding body cavity communicating with the duct, and a substantially one-piece diaphragm extending across the mouth of the head and having its outer face formed with an extended series of alternate ribs and grooves with air passages following the contour of the grooves, the diaphragm being relatively rigid and the head yieldable to pressure to compress it into the hollow body of the cup. 75

2. A vacuum massage device comprising a cup-shaped body of resilient material with one end reduced into a hand hold and traversed by an axial duct to form an air duct, and the other end terminating in an expanded body portion with a relatively broad bearing surface, and a diaphragm of relatively unyielding material extending across the mouth of the cup and formed on its outer face into alternate ridges and grooves with the ridges in the plane of the mouth of the cup and the grooves having passages therethrough into the interior of the cup. 80

3. A vacuum massage cup comprising a cup-shaped body of resilient material with an axial termination ending in a hand receiving head having an air duct leading axially therethrough, said cup having an expanding body portion communicating with said duct, a diaphragm extending across the mouth of the head with said diaphragm having its outer face formed into an extended series of alternate ribs and grooves with air passages following the contour of the grooves, said diaphragm being vulcanized to the hollow body of the cup and formed thereby into a relatively rigid structure. 85

4. A vacuum massage device comprising a cup-shaped body of resilient material with one end reduced into a hand hold and traversed by an axial duct to form an air duct and provided with a finger receiving cavity for closing the duct, and the end of the body member remote from the finger receiving cavity being formed into alternate ridges and grooves with the ridges in the plane of the mouth of the cup and the grooves having passages therethrough into the interior of the cup and the diaphragm being relatively rigid. 90

5. A vacuum massage cup comprising a cup-shaped body of resilient material having an expanded face provided with concen- 95

tric alternating series of ridges and grooves, with the ridges in the plane of the mouth of the cup and the grooves having passages therethrough into the interior of the cup, 5 and the end of the cup remote from the ridges and grooves being formed into a hand hold with an axial passage therethrough terminating in a cavity constituting a finger receptacle whereby to close the duct to thus retain vacuum conditions established in the 10 cup by pressure exerted thereon.

In testimony whereof, we affix our signatures hereto.

RALPH S. THOMPSON.
CARL F. DOSCHER.
